HYDRAULIC BRAKE APPARATUS

Henry F. Schmidt, Lansdowne, Pa., assignor to
Westinghouse Electric & Manufacturing Com-
pany, East Pittsburgh, Pa., a corporation of
Pennsylvania

Application August 19, 1942, Serial No. 455,294

19 Claims. (Cl. 188—90)

In my application Serial No. 454,887, filed August 15, 1942, I have disclosed and claimed a hydraulic brake suitable for moderate or low speeds and it has the advantages of stability, self-regulation, and self-pumping.

The present invention relates to apparatus of the above character and it has for an object to provide a brake having the aforementioned advantages and which is more suitable for high speeds.

A further object of the invention is to provide a hydraulic brake of the self-pumping type wherein the pumps or pressure-developing devices are so arranged that their inlets are disposed adjacent to the glands to assure of liquid pressure imposed on the latter not exceeding that at the pump or device inlets.

A further object of the invention is to provide interfitting rotary and stationary ring members having buckets formed in adjacent faces to define a pair of annular rows of circulation chambers and wherein the stationary ring member has passages formed therein to provide for discharge of liquid from the circulation chambers.

A further object of the invention is to provide a hydraulic brake, having a pair of annular rows of circulation chambers disposed in opposed relation and defined by cooperating buckets formed in adjacent faces of a pair of rotary ring members and an intervening stationary ring member, wherein the column of liquid in each row of circulation chambers is balanced by the rotating column maintained by runner vanes attached to the outer faces of the rotary ring members.

A further object of the invention is to produce a hydraulic brake wherein the casing or stator cooperates with the rotor to define annular inlet chambers for supplying liquid to centrifugal pumps including vanes carried at the outer sides of rotor ring members cooperating with an intervening stator ring member to provide a pair of annular rows of circulation chambers supplied by the pumps and wherein an atmospheric pressure condition is maintained in the annular inlet chambers and centrally of the circulation chambers.

These and other objects are effected by the invention as will be apparent from the following description and claims taken in connection with the accompanying drawings, forming a part of this application, in which:

Fig. 1 is an elevational view of the improved brake showing the constant-level liquid supply tank in section;

Fig. 2 is a longitudinal sectional view of the brake shown in Fig. 1;

Figs. 3, 4 and 5 are transverse sectional views taken along the lines III—III, IV—IV and V—V, respectively, of Fig. 2, and viewed in the direction of the arrows;

Fig. 6 is a view, partly in longitudinal section, showing a modified form of brake; and,

Fig. 7 is a diagrammatic view illustrating the pressure-balancing feature.

The brake comprises a stator or casing, at 9, and a rotor, at 10. The rotor includes a spindle 11 and a pair of axially-spaced ring members 12 unitary with the spindle. The stator or casing 9 is provided with a ring member 13 extending between the ring members 12, the adjacent faces of ring members 12 and 13 being formed with laterally-open buckets 14 and 15 which cooperate to provide a pair of annular rows of circulation chambers, at 16. As the stator buckets face outwardly and the rotor buckets face inwardly, the hydraulic thrust developed by one row of circulation chambers is balanced by that of the other.

As shown, the stator or casing, at 9, is made in upper and lower halves 17 and 18 connected by bolts 19 and it provides a cylindrical chamber 20 for the ring members, the stator ring member 13 preferably fitting in an annular groove or countersunk seat 21 formed in the interior cylindrical wall of the chamber so as to be firmly attached to the casing stator in order to resist any tendency to lateral or rotary displacement thereof relative to the latter.

The casing or stator, at 9, has trunnions 22 fitting bearings 23, preferably of the antifriction type, carried by the pedestals 24. The rotor is supported by journals 25 fitting bearings 26 housed in and supported by the trunnions 22. At one end, the spindle has a portion 27 extending beyond the adjacent trunnion to provide for coupling of the brake rotor to a suitable machine.

Assuming liquid to be supplied to the circulation chambers, at 16, and the rotor to be rotating, then the stator and the rotor tend to be clutched together by means of the circulating liquid in the circulation chambers; and, if rotation of the stator is restrained, a braking effect or resisting torque is applied to the rotor.

As the braking effect is a factor by means of which the power of a machine connected to the rotor may be determined, the stator has an arm 28 bearing on the scale 29 used to weigh the force exerted thereon by the arm.

Liquid, for example, water, is supplied from an elevated constant-level tank 31 by a conduit 32 and liquid discharges from the brake through a

conduit 33. Liquid discharges from the conduit 32 into the stator or casing chamber 34 and it is supplied from the latter by stator passages 35 to the annular chambers 36 defined between the stator and the rotor and located outwardly of and adjacent to the rotor ring members 12. Any suitable end glands or seals 37 may be employed between the stator and the rotor to restrict leakage outwardly from the chambers along the spindle or rotor.

Centrifugal devices, at 39, supply liquid from the annular chambers 36 to the circulation chambers, at 16, and, as the annular chambers are, therefore, relieved of high pressure, leakage through the glands 37 is minimized.

Each device, at 39, is comprised by relatively wide runner vanes 40 attached to the outer faces of the rotor ring members 12 and by the chamber end walls 41 defining loose clearances with respect thereto. The peripheries of the rotor ring members 12 are spaced from the interior cylindrical wall of the chamber 20 to provide annular passages 42 for supplying liquid from the devices to the circulation chambers.

In Fig. 2, communication of the annular passages 42 with the circulation chambers is effected both by the radial annular spaces 43 between the adjacent rotary and stationary ring members and by the inclined ports 44 formed in the stator ring member 13, whereas, in Fig. 6, there is provided only the radial annular spaces 43 serving this purpose.

Liquid discharging from the circulation chambers enters an annular passage 45 formed by a peripheral groove 46 in the ring member 13 and covered by the stator or casing 9. The discharge conduit 33 communicates with the annular passage. In Fig. 2, the stator ring has ports 47 providing for discharge of liquid from the circulation chambers to the annular passage 45, whereas, in Fig. 6, discharge occurs through the annular radial spaces 48 defined between adjacent rotary and stationary ring members and annular passages 49 between the rotor and the inner periphery of the stator ring 13 to the annular space 50 formed by an inner groove 51 in the stator ring, the stator ring having radial ports 52 providing for flow from the space 50 to the annular passage 45.

In Fig. 2, the radial spaces 48 and the connecting annular passages 49a function to maintain hydraulic balance between the two rows of circulation chambers.

Stability and self-regulation of the brake are assured by providing for an atmospheric pressure condition centrally of the circulation chambers, at 16, and in the inlet chambers 36. Also, as the constant level tank 31 provides for a constant supply head for the brake, the valves 54 and 55 make possible a definite and controlled flow contributing to stability and certainty of operation.

As shown in Figs. 2 and 5, the annular inlet chamber 36 for each pressure-developing device has an atmospheric pressure condition maintained therein by a circumferential series of radial pipes 56 extending through the stator or casing wall. Preferably, the stator is provided with deflector rings 57 having annular lips 58 extending inwardly along the chambers 36, and which are curved in transverse section to provide concave grooves 59, the grooves cooperating with annular ribs 60 on the stator to form annular passages 61 of approximately U-shaped section providing for gradual and easy change in direc-

tion of flow for discharge to the pump inlets with a substantial outward radial component. Each of the rings 57 defines an annular space 62 with respect to the rotor and the inner ends of the pipe 56 extend through the lip 58 and communicate with such space. Thus, it is assured that liquid at each pump or pressure-developing device entrance is subject to atmospheric pressure without the means providing therefor interfering with flow to the device or operation to provide a rotating column of liquid.

An atmospheric pressure condition is maintained centrally of the circulation chambers, at 16, by passages 63 formed in the webs 64 separating the buckets 15, the passages communicating with the circumferentially-extending space 65 formed in the stator ring member 13. As shown, the annular passage or circumferential space 65 is provided by a counter groove 66 in the stator ring member 13 and covered by the plate ring 67 welded at its edges to the stator ring, the plate ring separating the circumferential space from the outer annular discharge passage 45. A circumferential series of radial pipes 68 extending through the casing wall and the ring plate 67 provides for maintenance of an atmospheric pressure condition in the circumferential space 65. As both the casing or stator 9 and its ring member 13 are made in halves to facilitate assembly, the space 65 is not a complete annulus, it being interrupted by end closure plates 69 adjacent to the joint.

While the pressure-developing devices, at 39, resemble centrifugal pumps, they operate only incidentally as pumps, the principal function thereof being to provide a rotating column of liquid whose centrifugal force is balanced by that of the circulation chamber column, as may be seen from Fig. 7. The radial dimension A of the centrifugal device column is greater than the radial dimension B of the circulation chamber column, for the reason that the radius R of the pressure-developing device column is greater than the radius r of the circulation chamber column, it being remembered that centrifugal force varies as the square of the velocity and inversely as the radius. As each centrifugal device has relatively wide runner vanes 40 and liberal clearance thereof with respect to the wall surfaces 41, as atmospheric pressure is maintained centrally of each pressure-developing device and of the circulation chambers, and as the inner portions of the spaces between runner vanes are never filled with liquid, it is assured that the device will operate as a load-balancing or equalizing one. The rate at which liquid is supplied to the runner and the vane width are such that liquid enters as a spray. Therefore, the device functions as a centrifuge to separate air, this action being aided by the liberal clearance. While the centrifugal device functions incidentally as a pump, such functioning is not essential so far as load-balancing or equalizing is concerned, for it will be apparent that the apparatus will provide balanced columns irrespective of how liquid is supplied to form the latter.

The valves 54 and 55 adjacent to the brake and in the supply and discharge conduits provide for definite or controlled flow. Assuming that the discharge valve 55 is set for flow sufficient to avoid overheating or steaming, then the effect of opening the valve 54 wider is to increase the orifice area provided thereby and to increase the supply rate of liquid to the annular inlet cham-

bers 36 for the pumps. Both the head of the centrifugal pumps, at 39, and the head of the circulation chambers, at 16, increase, as any tendency of the centrifugal pump column to increase is accompanied by an increase in the radial thickness of the circulating streams in the associated circulation chambers, and vice versa, so as to maintain equilibrium of pressures due to centrifugal force of liquid in each pump and in the connected circulation chambers; and the centrifugal heads will continue to increase until the increase in centrifugal head of the circulation chambers is sufficient to provide a pressure difference across the discharge orifice defined by the discharge valve to equalize in-flow and out-flow of liquid. However, as the centrifugal heads increase, the braking effort is increased, with the result that the rotor speed is reduced. Hence, if it is desired to ascertain the power of a machine at a given speed and having a tachometer to observe the machine speed, then the flow of liquid is adjusted by relative adjustment of the valves 54 and 55 until the machine speed is at the desired point, and then the magnitude of the resisting torque is ascertained by means of the scale 29.

The provision of an atmospheric pressure condition at each pump inlet assures that the pressure of liquid supplied to the associated circulation chambers is entirely due to the pump, with the result that the apparatus is self-regulating; and, by having both the pump inlet space and the circulation chambers subject to atmospheric pressure, a balanced relation is maintained, with the result that operation is stable, the resisting torque being varied by relative valve adjustment and being maintained uniform at any selected adjustment. Furthermore, as shown in Fig. 2, the two rows of circulation chambers are equalized or placed in hydraulic balance by the connecting passageway constituted by the radial spaces 48 and the annular passage 49a.

From the foregoing, it will be apparent that, by having one row of circulation chambers in opposed relation to the other, the hydraulic thrust of one is balanced by that of the other. The design is such that structural material may be selected and disposed for operation at high speeds and to withstand high pressures. Furthermore, the maintenance of an atmospheric pressure condition at each pump inlet and centrally of the circulation chambers and the provision of centrifugal pumps, including runner vanes attached to the rotor, assures of a hydraulic brake which is self-pumping, self-regulating, and stable.

While the invention has been shown in several forms, it will be obvious to those skilled in the art that it is not so limited, but is susceptible of various other changes and modifications without departing from the spirit thereof, and it is desired, therefore, that only such limitations shall be placed thereupon as are specifically set forth in the appended claims.

What is claimed is:

1. In a hydraulic brake, a casing, a rotor within the casing, a pair of axially-spaced ring members unitary with the rotor, a ring member interposed between the rotor ring members, and fixed to the interior of the casing, a pair of annular rows of circulation chambers formed by complementary buckets provided at opposed faces of casing and rotor ring members, means for supplying liquid to the circulation chambers and including centrifugal devices comprising runner

vanes connected to the rotor ring members at the outermost sides thereof, and means including passages formed in the casing ring member and providing for discharge of liquid from the circulation chambers.

2. In a hydraulic brake, a casing, a spindle, a pair of axially-spaced ring members carried by the spindle, a ring member carried by the casing and interposed between the spindle ring members, a pair of annular rows of circulation chambers formed by complementary pockets provided in opposed faces of the casing and spindle ring members, centrifugal devices including runner vanes carried by the spindle ring members at the outermost sides thereof, and means including annular passages defined between the peripheries of the spindle ring members and the interior of the casing for connecting said devices to the circulation chambers.

3. The combination as claimed in claim 2 with means for maintaining an atmospheric pressure condition at the inlet space of each centrifugal device and centrally of each of the circulation chambers.

4. In a hydraulic brake, a casing providing a cylindrical chamber having radial end walls, a rotor having a pair of integral and axially-spaced ring members disposed in the chamber, a ring member fixed interiorly to the casing and extending inwardly between the rotor ring members, circulation chambers formed by buckets provided at adjacent faces of the rotor and casing ring members, runner vanes formed on the outermost faces of the rotor ring members and cooperating with said end walls to provide centrifugal pressure-developing devices, means for supplying liquid to the inlets of the devices, means including annular passages defined between the interior cylindrical wall of the casing and the peripheries of the rotor ring members for supplying liquid from the outlets of the devices to the circulation chambers, and means including passages formed in the casing ring member providing for discharge of liquid from the circulation chambers.

5. In a hydraulic brake, a casing, a rotor within the casing and comprising a spindle and a pair of axially-spaced ring members unitary with the latter, a ring member fixed to the interior of the casing and interposed between the first ring members, a pair of annular rows of circulation chambers formed by complementary rows of buckets provided at opposed faces of the rotor and casing ring members, the buckets of each row being separated by partitions, means for supplying liquid to the circulation chambers including centrifugal devices comprising runner vanes connected to the rotor ring members at the outermost sides thereof, said casing and rotor cooperating to provide annular chambers open to the inlets of said devices, means including passages formed in the casing for supplying liquid to said annular chambers, means providing for discharge of liquid from the circulation chambers and including an annular passage formed by an annular groove provided in the casing ring member and covered by the casing, means providing for the maintenance of an atmospheric pressure condition in each of said annular chambers, and means providing for the maintenance of an atmospheric pressure condition centrally of the circulation chambers and including a circumferentially-extending space formed within the casing ring member and communicating with passages formed in the rotor partitions and opening into spaces which are

central with respect to the circulation chambers.

6. In a hydraulic brake, a casing, a rotor within the casing and comprising a spindle and a pair of axially-spaced ring members unitary with the latter, a ring member fixed to the interior of the casing and interposed between the first ring members, a pair of annular rows of circulation chambers formed by complementary rows of buckets provided at opposed faces of the rotor and casing ring members, the buckets of each row being separated by partitions, means for supplying liquid to the circulation chambers including centrifugal pumps comprising runner vanes connected to the rotor ring members at the outermost sides thereof, said casing and rotor cooperating to provide annular chambers open to the pump inlets, means including passages formed in the casing for supplying liquid to said annular chambers, means providing for discharge of liquid from the circulation chambers and including an annular passage formed by an annular groove provided in the casing ring member and covered by the casing, means providing for the maintenance of an atmospheric pressure condition in each of said annular chambers, and means providing for the maintenance of an atmospheric pressure condition centrally of said circulation chambers and including a circumferentially-extending space formed within the casing ring member and passages formed in the partitions separating the casing ring member buckets for connecting said space to spaces which are central of the circulation chambers.

7. In a hydraulic brake, a casing providing an interior cylindrical chamber, a spindle in the casing, glands for sealing against leakage from the interior of the casing toward the bearings, a pair of axially-spaced ring members in said chamber and unitary with the spindle, a ring member carried by the casing and extending inwardly between the rotor ring members, said casing cooperating with the spindle to provide annular chambers opening into said cylindrical chamber through the end walls thereof, runner vanes carried by the outermost sides of the rotor ring members and cooperating with said end walls to provide centrifugal pumps whose inlets are open to said annular chambers, means including annular passages formed between the peripheries of the motor ring members and the interior cylindrical wall of the chamber for connecting the pump outlets to the circulation chambers, means for supplying liquid to the circulation chambers, and means providing for the discharge of liquid from the circulation chambers.

8. The combination as claimed in claim 7 with means providing for the maintenance of an atmospheric pressure condition in the annular chambers and centrally of the circulation chambers.

9. In a hydraulic brake, a casing providing an interior cylindrical chamber, a spindle in the casing, bearings at the ends of the casing for supporting the spindle, glands for sealing against leakage from the interior of the casing toward the bearings, a pair of axially-spaced ring members in said chamber and unitary with the spindle, a ring member carried by the casing and extending inwardly between the rotor ring members, said casing cooperating with the spindle to provide annular chambers opening into said cylindrical chamber through the end walls thereof, runner vanes carried by the outermost sides of the rotor ring members and cooperating with

said end walls to provide centrifugal pumps, said vanes having their inner ends approximately at the outer boundaries of the annular chambers, means including radial passages formed in the casing for supplying liquid to the annular chambers, rings carried by the casing and having annular lips which extend along the annular chambers and having their inner ends disposed adjacent to the outermost sides of the rotor ring members, said lips being curved in cross section to provide, with respect to the casing, annular passages communicating with said radial passages and to provide for gradual change in direction of liquid received from the last-named annular passages so that liquid is supplied to the spaces between runner vanes with an outward component of direction, and means providing for discharge of liquid from circulation chambers and including an annular passage formed by an annular groove provided in the casing ring and covered by the casing.

10. In a hydraulic brake, a casing providing an interior cylindrical chamber, a spindle in the casing, bearings at the ends of the casing for supporting the spindle, glands for sealing against leakage from the interior of the casing toward the bearings, a pair of axially-spaced ring members in said chamber and unitary with the spindle, a ring member carried by the casing and extending inwardly between the rotor ring members, said casing cooperating with the spindle to provide annular chambers opening into said cylindrical chamber through the end walls thereof, runner vanes carried by the outermost sides of the rotor ring members and cooperating with said end walls to provide centrifugal pumps, said vanes having their inner ends approximately at the outer boundaries of the annular chambers, means including radial passages formed in the casing for supplying liquid to the annular chambers, rings carried by the casing and having annular lips which extend along the annular chambers and having their inner ends disposed adjacent to the outermost sides of the rotor ring members, said lips being curved in cross section to provide, with respect to the casing, annular passages communicating with said radial passages and to provide for gradual change in direction of liquid received from the last-named annular passages so that liquid is supplied to the spaces between runner vanes with an outward component of direction, means providing for discharge of liquid from the circulation chambers and including an annular passage formed by an annular groove provided in the casing ring and covered by the casing, means providing for the maintenance of an atmospheric pressure condition in each of said annular chambers and including a circumferential series of tubes whose outer ends communicate with the atmosphere externally of the casing and whose inner ends extend through the curved lips and communicate with the spaces between the latter and the spindle, and means providing for the maintenance of an atmospheric pressure condition centrally of each of said circulation chambers and including a circumferentially-extending space formed within the casing ring member and a circumferential series of radial tubes whose outer ends communicate with the atmosphere and whose inner ends communicate with the circumferentially-extending space.

HENRY F. SCHMIDT.
